CLAIM

The ornamental design for handle grip for power tool, as shown and described below.

DESCRIPTION

FIG. 1 is a left perspective view of a handle grip for power tool showing our new design;

FIG. 2 is a right perspective view thereof;

FIG. 3 is a top plan view thereof;

FIG. 4 is a bottom plan view thereof;

FIG. 5 is a left side view thereof;

FIG. 6 is a right side view thereof;

FIG. 7 is a rear view thereof; and,

FIG. 8 is a front view thereof.

The broken lines illustrate the environment of a power tool and form no part of the claimed design.
